(57) **CLAIM**

The ornamental design for a birder's gear belt, as shown.

DESCRIPTION

FIG. 1 is a front elevation view of a birder's gear belt showing our new design, with the pockets shown closed;

FIG. 2 is a rear elevation view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front elevation view, with the center pocket shown in a rolled up condition and the two outer pockets closed;

FIG. 8 is a rear elevation view thereof;

FIG. 9 is a top plan view thereof;

FIG. 10 is a bottom plan view thereof;

FIG. 11 is a left side elevation view thereof;

FIG. 12 is a right side elevation view thereof;

FIG. 13 is a front elevation view of a birder's gear belt, with the pockets shown open;

FIG. 14 is a rear elevation view thereof;

FIG. 15 is a top plan view thereof;

FIG. 16 is a bottom plan view thereof;

FIG. 17 is a left side elevation view thereof; and,

FIG. 18 is a right side elevation view.
